UNITED STATES PATENT OFFICE

150,692

DESIGN FOR AN AIRPLANE

Charles S. Glasgow, Los Angeles, and Carlos C. Wood, West Los Angeles, Calif., assignors to Douglas Aircraft Company, Inc., Santa Monica, Calif.

Application October 22, 1946, Serial No. 134,170

Term of patent 14 years

(Cl. D71—1)

To all whom it may concern:

Be it known that we, Charles S. Glasgow and Carlos C. Wood, citizens of the United States and residents, respectively, of Los Angeles, in the county of Los Angeles and State of California, and Brentwood Heights, West Los Angeles, in the county of Los Angeles and State of California, have invented a new, original, and ornamental Design for an Airplane, of which the following is a specification, reference being had to the accompanying drawings, forming a part thereof.

Figure 1 is a top perspective view of an airplane in flight showing our new design;

Figure 2 is a side elevational view of the subject airplane depicted in Figure 1 with the landing gear extended and the airplane at rest on the ground;

Figure 3 is a bottom plan view of the airplane depicted in Figures 1 and 2;

Figure 4 is a front elevational view of the airplane depicted in Figures 1, 2 and 3 with the landing gear extended and the airplane at rest on the ground.

We claim:

The ornamental design for an airplane, substantially as shown.

CHARLES S. GLASGOW.
CARLOS C. WOOD.
